(57) **CLAIM**

I claim the ornamental design for a gripping handle for an infant car seat, as shown and described.

DESCRIPTION

FIG. 1 is a perspective view of a gripping handle for an infant car seat, showing my new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof.

The broken lines shown in FIGS. 1-6 are for illustrative purposes only and form no part of the claimed design.
